UNITED STATES PATENT OFFICE.

JAMES E. WHEAT, OF BRIDGEPORT, CONNECTICUT.

FLUSH HINGE.

No. 918,802.

Specification of Letters Patent.

Patented April 20, 1909.

Application filed January 2, 1909. Serial No. 470,316.

To all whom it may concern:

Be it known that I, JAMES E. WHEAT, a citizen of the United States, and resident of Bridgeport, in the county of Fairfield and 5 State of Connecticut, have invented certain new and useful Improvements in Flush Hinges, of which the following is a specification.

My invention relates to an improved form 10 of flush hinge so called, that is, a hinge which when used intermediate of a table and leaf of a sewing machine and set into a mortise thereof will finish flush with the surface and not have an extended knuckle as is the case 15 with sewing machine hinges for this purpose now upon the market.

It is the purpose of the invention to produce a hinge of the above kind that will be durable, simple, and practicable, thus insuring, 20 a long period of usefulness and their general application to not only all styles of sewing machines, but other things, as for instance drop leaf tables, pianos, etc., and to construct the hinge in any way which will 25 allow it to be made from two parts of sheet metal and a single piece of wire all of which can be inexpensively produced by automatic machinery.

Upon the accompanying sheet of drawings 30 forming a part of this specification, similar characters of reference denote like or corresponding parts throughout the several figures and of which,

Figure 1, shows a top plan view of one of 35 my improved flush hinges. Fig. 2, is a side edge view of the hinge shown in Fig. 1, Fig. 3, is also a side edge view of the hinge, in an open position, and Fig. 4, is a bottom plan view of the hinge.

40 Referring in detail to the reference characters marked upon the drawings 5 represents the two leaves of the hinge which are alike in construction and each contain the usual screw holes 6, any number of which may be employed. These leaves may obviously be 45 of any suitable shape or design as may be best suited in style to the particular purpose for which they are employed.

The outer edges 7 of the two leaves are 50 bent over and disposed at a right angle to the face of the leaf forming a perfectly round corner on the inner top edge of each leaf which extends across the entire depth of the hinge and thus also forms a correspondingly 55 transverse concave socket 8 upon their under

side. The leaves are each provided with a pair of slots 9 in their abutting surfaces and are arranged to register with the corresponding slots in the opposite leaf so that when the leaves are assembled they will operate in conjunction with each other. These slots extend through the bent portion of the leaves as will be noted from the drawings and serve to accommodate an elongated shaped link 10 which is formed of a single piece of wire. 60 In practice this link is first bent substantially a U shape, in which form it is inserted through the respective slots of the leaves and then the ends are bent toward each other and disposed into the concaved pockets 8 before mentioned, see Fig. 4. The two short end portions of this link 10 are thus arranged through the slot openings in the bent portions of the two leaves while the longitudinal side portions of the link lay across the underside and in the concave pocket 8 before mentioned. The purpose of the link is obviously to snugly hold the two bent operating faces of the leaves together and to retain the leaves in proper positions relative to each other when in their various positions. 70

With the parts in the position shown in Figs. 1 and 2 and secured to the table and leaf of a cabinet as indicated in dotted lines the effect of the movable leaf of the hinge 75 when being raised would be to roll or turn back upon the rounded corner of the fixed leaf carrying therewith the link, which in all positions hugs the pockets thereof in a way to prevent any sliding movement of one leaf 80 upon the other. In practice I find that when properly made and applied the hinges are very effective and operate satisfactorily. 85

90 From the foregoing it will be seen that when this hinge is spread as shown in Figs. 1 and 2, no part of either the leaves or link extends above the top surface thereof, and that a smooth finish is produced throughout save the small transverse pocket produced at the intersection of the rounded corners, 95 which is obviously not objectionable. 100

Having thus described my invention what I claim and desire to secure by Letters Patent is:—

1. In a flush hinge of the class described, 105 the combination of a pair of leaves having their inner parallel edges abutting against each other when the leaves are in alinement, and the upper surfaces of such edges smoothed and rounded to form an operating 110

joint, a single wire link arranged below the face of the leaves and adapted to hold the operative ends of the leaves snugly together.

2. In a flush hinge of the class described,
5 the combination of a pair of leaves having
their inner abutting smooth edges turned
down at an angle to the face of the leaves
forming smooth, rounded abutting opera-
tive edges, oppositely arranged openings in
10 the rounded abutting portions of the leaves,
a single wire link arranged in the openings

and extending along under the leaves in a
way to snugly retain the operative abutting
edges of the two leaves together.

Signed at Bridgeport, in the county of ¹⁵ Fairfield, and State of Connecticut, this 31st
day of December, A. D., 1908.

JAMES E. WHEAT.
